UNITED STATES PATENT OFFICE.

CLEMENT HENRY STEVENS, OF HIGH WYCOMBE, ENGLAND.

PNEUMATICALLY-OPERATED PERCUSSIVE HAND TOOL.

Application filed October 20, 1924, Serial No. 744,726, and in Great Britain September 26, 1924.

This invention relates to pneumatically operated percussive hand tools and has for its object to provide an improved construction thereof, and in particular an improved 5 construction and arrangement of the valves for such tools.

According to the present invention the disc valve which works in a chamber between ported seatings is mounted in a valve box consisting of a valve chamber formed as an aperture in a spacing disc located or sandwiched between a pair of ported discs or valve seats enclosed between housing discs or members, the latter being provided 10 with lips, flanges, or equivalent projections for centralizing the enclosed discs. A suitable dowel pin may be provided to assist in accurately assembling the parts and ensuring that the ports in the discs and housings 15 are in the correct register.

An ejector device may be provided in the lower or one of the housings, the said ejector being blown or operated by a jet of air passing through a suitable port and a connecting passage, the said ejector being so arranged and operating as to withdraw air from between the piston and the snap or tool on the striking stroke and thus prevent cushioning taking place by compression of 20 the air between the said piston and the tool or snap.

One construction of pneumatic hammer or hand tool embodying the present invention will now be described with reference to 25 the accompanying drawings, wherein,

Fig. 1 is a plan of the valve housings,

Fig. 2 is a section on line 2—2 of Fig. 1.

Fig. 3 is a section on line 3—3 of Figs.

1 and 2.

Fig. 4 is a section on line 4—4 of Fig. 1.

Fig. 5 is a section on line 5—5 of Fig. 1.

Fig. 6 is a section on line 6—6 of Figs.

1 and 5.

Fig. 7 is a longitudinal section of the complete tool.

Figure 8 is a longitudinal section taken through the assembled tool and handle on an enlarged scale. Figure 8 is also a horizontal section similar to Figure 2, but showing the valve in the opposite position, the course of the air being indicated by the arrows.

Referring now to the drawings, the valve box or chamber consists of an upper housing disc or member *a* a distance piece or spacing disc *d* having a circular hole in

its centre forming the valve chamber *u* in which the distributing valve, consisting of a plate *v*, fits loosely and is free to work up and down and to seat itself either on the 60 upper or lower valve seats formed by the discs *c c'*.

The said valve seats *c c'* and the distance piece *d* are kept concentric and held in position by lips *f* and *f'* formed on the upper 65 and lower housings *a* and *b*.

A dowel pin *t*, Figs. 2 and 4, is provided to hold the different parts in their relative positions.

Air ports *g* and *g'* Fig. 5, are provided to 70 carry air under pressure from any suitable source of supply to the under valve face, and air ports *j* and *j'*, Fig. 6, serve similarly to carry air under pressure from the lower valve face to the working cylinder of the 75 hammer or tool behind the piston *y*.

Similarly, air ports *l l'*, Fig. 1 and Fig. 4 carry air under pressure to the upper valve face and ports *m* and *m'* Fig. 4, carry 80 air under pressure from the upper valve face via port *n*, Fig. 4, to the air passage *o* in the cylinder to the underside of the piston *y* at *x*, Fig. 7.

An ejector *r*, Fig. 2, is provided in the lower housing *b* adapted to be blown or operated by a jet of air passing through the small port *q*, Fig. 2, and the suction hole *s*, Fig. 3, passes from the port *n*, Figs. 3 and 4, into the chamber of the ejector.

The valve box comprising the beforementioned assembled discs and housings is located on top of the working cylinder Fig. 7, and is held in position by screwing on the hammer handle in the usual manner.

The method of working is as follows:— 95

High pressure air is admitted from the handle of the tool to the top face of the upper housing *a* of the valve box and passes down ports *g g'* and *h h'*, Figure 5, to the lower valve face thereby raising the valve as 100 in Figures 6 and 8 and thence via ports *j* and *j'* to the cylinder driving the piston *y*, Fig. 7, forward and causing it to strike the snap or tool in the usual manner, the rear edge of the piston *y* uncovering the exhaust port *p* and thus causing the pressure in the valve chamber below the valve to drop, the valve being then changed over by reason of the high pressure air entering ports *l* and *l'* (Figs. 1 and 4.) The valve then being 105 seated on its lower face, as shown in Fig. 4, high pressure air passes from ports *l* and *l'* 110

via ports m and m' and port n into passage o entering the cylinder at x and driving the piston back until the exhaust port p is open by the edge of the piston which thus causes the pressure in the valve chamber to drop. The valve then changes over to its original position against the upper valve face by reason of the high pressure air entering the lower face by ports g h and g' h' and the operation is continuously repeated.

The ejector v is arranged to draw air from between the piston and the tool via ports o s and port n on the forward or striking stroke compressed air flowing from the under side of valve V through passage g , as indicated by the arrows, and exhausting the air in space x and ports o , s , and thus prevent cushioning by compressed air taking place between the piston and the snap.

The jet hole q from the lower valve face to the ejector is closed by the valve during the return stroke of the piston, Fig. 2.

What I claim as my invention and desire to secure by Letters Patent is:—

1. A pneumatically operated percussive hand tool comprising the combination of a cylinder, a piston, a handle and a valve box comprising a disc valve, an annular spacing disc surrounding said valve, a pair of removable ported valve seats enclosing said valve and annular spacing disc and consisting of flat plates having ports consisting of simple through holes, a pair of ported valve housings provided with flanges on their outer circumferences for surrounding and centralizing the said ported valve seats and annular spacing disc, the ports opening on the inner faces of the said valve housings coinciding with the ports in the flat plates forming the renewable valve seats, means for admitting air under pressure to said valve box and conveying said air to the required ports in the cylinder, an ejector embodied in one of the housing discs, means for supplying a jet of air to said ejector for operating the same and withdrawing air from between the piston and the tool on the striking stroke of the said piston whereby cushioning by air between the piston and the said tool is avoided, means for admitting air under pressure to said valve box and means for conveying the said air to the required ports in the cylinder and to the ejector in the valve box housing.

faces of the said valve housings coinciding with the ports in the flat plates forming the renewable valve seats, means for admitting air under pressure to said valve box and conveying said air to the required ports in the cylinder. 40

2. A pneumatically operated percussive hand tool comprising the combination of a cylinder, a piston, a handle and a valve box comprising a disc valve, and annular spacing disc surrounding said valve, a pair of removable ported valve seats enclosing said valve and annular spacing disc and consisting of flat plates having ports consisting of simple through holes, a pair of ported valve housings provided with flanges on their outer circumferences for surrounding and centralizing the said ported valve seats and annular spacing disc, the ports opening on the inner faces of the said valve housings coinciding with the ports in the flat plates forming the renewable valve seats, means for admitting air under pressure to said valve box and conveying said air to the required ports in the cylinder, an ejector embodied in one of the housing discs, means for supplying a jet of air to said ejector for operating the same and withdrawing air from between the piston and the tool on the striking stroke of the said piston whereby cushioning by air between the piston and the said tool is avoided, means for admitting air under pressure to said valve box and means for conveying the said air to the required ports in the cylinder and to the ejector in the valve box housing. 50

CLEMENT HENRY STEVENS.
